JOHN N. HAHN, OF CLEVELAND, OHIO.

PACKING-CASE FOR FRAGILE ARTICLES.

1,156,074.

Specification of Letters Patent. Patented Oct. 12, 1915.

Application filed October 8, 1914. Serial No. 865,611.

To all whom it may concern:

Be it known that I, JOHN N. HAHN, a citizen of the United States, residing at Cleveland, in the county of Cuyahoga and State of Ohio, have invented certain new and useful Improvements in Packing-Cases for Fragile Articles, of which the following is a specification.

This invention pertains to an improvement in packing cases for fragile articles, such, especially, as glass or porcelain globes, and the invention consists in a case made, preferably, of suitably heavy corrugated paper or paper board of a standard and accepted grade which meets the regulations of railroads for shipping purposes, and, in the example of case shown in the drawings, has two so-called trays by which the globe is supported in the case. These also, in the style herein shown, are of somewhat different construction though not necessarily in all cases, as will hereinafter more clearly appear.

In the accompanying drawings, Figure 1 is a sectional elevation of the case, box or receptacle on a line corresponding to 1—2, Fig. 3, and Fig. 2 is a like elevation on a line corresponding to line 2—1, Fig. 3. Fig. 3 is a cross section or plan on line 3—3 Fig. 1, and Fig. 4 is a perspective view of the lower or bottom supporting tray. Fig. 5 is a reduced plan view of the top tray or support.

The case or box proper is indicated by C, and as already stated, is preferably and usually made of a suitable grade of fairly stiff corrugated paper board, which combines lightness with strength adapted to withstand packing and shipping. In the present views, this article is shown as rectangular in cross section and has folding end flaps 2 which meet at the center, so that the said trays and the globes G therein can be inserted in the most convenient ways at the ends of the case. Of course the case might be made with a permanently closed bottom and an open top, but the present construction is deemed best for several reasons and particularly for convenience in placing the comparatively fitting trays D and E in the respective ends thereof. The said trays or members D and E are alike in certain particulars, both having side wings 3 and 4, respectively, adapted to be turned to right angles from a flat position,

but with this difference, that the wings 3 in tray D are shown as considerably wider than the wings 4 in tray E. These differences, however, are marginal, and in either case need have only such depth as to positively hold or carry the globe out of possible contact with either the top or the bottom of the receptacle and thus avoid danger of breakage by end thrusts. Possibly, in the present showing the depth of both said members is more than is actually required, both said members are supposed to afford a very positive support for the globe in about the position thereof shown and without any material yield thereof either way notwithstanding the support afforded at both ends is also resilient enough to prevent possible breakage in the globe however handled in the shipping, assuming that ordinary precaution or care is exercised. Thus, the upper tray D has not only the four wings 3 at its four sides adapted to be turned to right angles into supporting position in the wall of the case C, but it has also a series of radially disposed tapered spurs or tongues 5 extending inward to nearly the middle thereof from a circular crease at the base of said spurs, the said crease being in the upper side so as to permit said globe and stand, say, as seen in Figs. 1 and 2 in supporting relations to the globe. The said crease as to each spur being a portion of a complete circle or a segment thereof the shoulders of the crease are encountered when the spurs are bent substantially as shown and resistance to further bending begins to be manifest and serves at last as a definite stop to the turning of said spurs on their hinges. This, then makes a very safe top protection or guard for the globe with enough yield to prevent possible injury or breakage in handling and shipping as well as preventing breakage from direct end thrust. It will be noticed, also, that the point of contact of the said spurs 5 with the globe is near their base where the resistance is greatest, and the said tray has a border b inside all around from which the spurs project toward the center on radial lines.

A somewhat similar construction obtains in Figs. 3 and 4 in the tray E. Thus, the said tray has spurs 6 struck radially from segmental creases at their base in the border b' and a series of radial tapered panels or supports 7 between said border and the cen-

ter 8. The said center and panels are integral with said border, and the panels alternate with the said spurs and correspond thereto in radial disposition, shape and size, 5 or approximately in the present showing, the object being to have a strong bottom support for the globe and side brace or studs adapted to confine the globe at its base and hold it from sliding laterally. The said 10 spurs when bent to upright position become fairly rigid on account of the shoulders in their base bearing against the opposite shoulder of the crease on a curved line. Practically the bottom member E may be regarded 15 as having a continuous top, less the spurs 6 struck up therefrom and at such intervals as will afford the lateral support and confinement needed.

As to the segmental creases at the base of 20 the spurs 7, it should be understood that the stock is not creased between said spurs across the panels 7 but only at the base of the spurs, and the said creases are in the top side, necessarily. It will be seen, also, that if the 25 box or case be inverted so that the top really becomes the bottom for the time being and the weight of the globe comes on the spurs 5, the said spurs have sufficient strength to carry the globe because the circle on which 30 the crease is struck at the base of said spurs is narrower than the full top width of the globe, and the globe therefore rests on the base portions of said spurs and cannot possibly press through so as to strike the lids or 35 flaps 2 of the box. It follows that by providing a supporting tray or trays with spurs struck up in this way the endwise thrust or weight of the globe is taken care of and no additional precautions are required. The 40 borders b and b' are of such width as will keep the globe sufficiently apart from the wall of the box and the present globe G has a flange g about its bottom opening on which it rests. Of course I do not mean to limit 45 the invention to the accommodation of only this particular style of globe because the same principle of construction can be employed with globes of other shape and of different sizes and also for lamp shades and the 50 like.

An important feature herein is the relation of the spurs 5 to the top or end flaps 2 of the case. Presumably, in all shipments by this parcel, the object or article shipped 55 has or will have a top portion adapted to be projected through or into the top tray about as shown with the present globe and I mean to rely on the border portion at the edge of said spurs for much or all the spring resistance that this end of the receptacle need 60 provide for the globe, but it also occurs that globes or articles of different or smaller width and of different shape will be shipped in this receptacle of a suitable size, larger or 65 smaller. In such case the article may be too

small to infringe on said base edge of the spurs and will be held only by the spurs with such spring or resilient support as they may afford. Hence, the relation between the open spurs 5 and the folded top as shown with the 70 points or ends of the spurs in contact with said top. Usually the said spurs are supposed to sustain about the relation shown when they are in use, and if they were open a less distance they still would come into end 75 contact with the top of the box if the box were inverted and the weight of the contents rest on the said spurs. Of course, it is understood that when the box is occupied for shipping, the flaps at both ends are closed and held down or sealed by any suitable means, so that it may occur in shipping that the top of the box will be down although this is not deemed to be the best way. The side wings 80 3 rest against the base of said flaps.

By extending the several radial openings o 85 from which the spurs are cut to the base of the spurs and having comparatively narrow strips 7 between said opening the top of the tray E is given the character of a spring 90 support for the article carried thereon and of course I can carry articles or globes varying considerably in size on a bottom like this because the total support of the strips or arms 7 will readily sustain the load while 95 the spurs can be turned to any desired inward inclination to engage and hold considerably smaller globes than the extreme or maximum size shown herein. If the globe were half as wide it would be inclined accordingly and would afford all the lateral support necessary as well as a resilient base support.

By the foregoing constructions of the two 105 trays, a spring engagement is provided for both ends of the globe and the box can ride on either end with perfect safety to the contents. However in all shippings the boxes are supposed to be placed on board or in storage with the bottom proper downward. 110

What I claim is:

1. A shipping box for globes or shades comprising the combination of a case having its side walls spaced to clear the globe or shade and having end closures spaced to 115 clear the globe or shade and two marginally flanged trays independent of the case and withdrawable therefrom and insertible therein and spaced to engage the globe or shade and hold it clear of the case and each having its entire flange fitting inside the case and contacting with a case closure and whereof one tray is provided with a circular row of inwardly extending fingers 120 adapted to constitute a concave seat arranged between the tray and the adjacent case closure for the reception of one end of the globe or shade, and whereof the other tray is provided with a group of spaced tongues 125 and with a solid center part adapted to over- 130

lie the other end of the globe or shade with the tongues in engagement with the curved wall of the shade or globe.

2. A shipping box for globes or shades comprising the combination of a knock-down corrugated strawboard case having its side walls spaced to clear the globe or shade and having end closures spaced to clear the globe or shade, and two marginally flanged detachable trays spaced to engage the globe or shade and hold it clear of the case and each having its entire flange fitting inside the case and contacting with a case closure and whereof one tray is provided with a circular row of inwardly extending fingers adapted to constitute a concave seat arranged between the tray and the adjacent case closure for the reception of one end of the globe or shade, and whereof the other tray is provided with a group of spaced tongues and is adapted to overlie the other end of the globe or shade with the tongues in engagement with the curved wall of the shade or globe.

25 3. A shipping box for globes or shades comprising the combination of a case hav-

ing its side walls spaced to clear the globe or shade and having two ends each consisting of four flaps adapted to be folded together to form end closures spaced to clear 30 the globe or shade, and two marginally flanged trays spaced to engage the globe or shade and hold it clear of the case and each having its flange fitting inside the case and contacting with a case closure and whereof 35 one tray is provided with a circular row of inwardly extending fingers adapted to constitute a concave seat arranged between the tray and the adjacent case closure for the reception of one end of the globe or shade, 40 and whereof the other tray is provided with a group of spaced tongues and is adapted to overlie the other end of the globe or shade with the tongues in engagement with the curved wall of the shade or globe, substantially as described.

In testimony whereof I affix my signature in presence of two witnesses.

JOHN N. HAHN.
